[57] CLAIM

The ornamental design for a gas pump nozzle handle holder, as shown and described.

DESCRIPTION

FIG. 1 is a front elevational view of a gas pump nozzle handle holder showing my new design;

FIG. 2 is a right side elevational view thereof;

FIG. 3 is a rear elevational view thereof;

FIG. 4 is a left side elevational view thereof; and,

FIGS. 5 and 6 are respectively bottom and top plan views thereof.
